UNITED STATES PATENT OFFICE

JULIAN W. BOURNIER, OF TAMPA, FLORIDA

BOAT DAVIT

Application filed January 30, 1929. Serial No. 336,269.

My invention relates to improvements in boat davits, and it consists in the combination, constructions, and arrangements herein described and claimed.

5 An object of the invention is the provision of a davit construction which will prevent upending of a boat during launching.

A further object of the invention is the provision of means for maintaining a boat a 10 fixed distance from the side of a ship, during launching.

A still further object of the invention is the provision of a davit which is vertically movable upon the sides of a ship so as to 15 bring the davit into close proximity of the water, thereby enabling the launching of a boat in a gradual manner.

A still further object of the invention is to provide a davit in which the use of blocks 20 and tackles are eliminated for effecting raising and lowering a boat.

Additional objects, advantages and features of invention will be apparent from the following description and drawings, forming 25 a part of this application, in which

Figure 1 is a cross sectional view of a ship having my davit installed thereon, the movement of the davit being indicated in dotted lines.

30 Figure 2 is a side view thereof,

Figure 3 is a fragmentary top plan view,

Figure 4 is a cross section on the line 4—4 of Figure 3.

Figure 5 is a cross section on the line 5—5 of Figure 1.

In carrying out my invention I provide a track 1, mounted upon the side of a vessel 2.

The track 1, in the present instance, comprises two spaced sections 3 constructed to 40 receive a carriage 4, slidably therebetween.

The carriage 4 comprises a pair of triangularly shaped supports 5 being connected by a float 6. Guide rollers 7 are mounted upon 45 one side of the support 5 and are of a size to be rotatably received within the tracks 1, as clearly shown in Figures 1, and 5. Upon the upper part of the carriage 4 hooks or eyelets 8 are provided, in which a cable 9 is 50 secured, the cable being trained about a pul-

ley 10, from whence it is extended to a winch or other hoisting means, not shown.

The upper horizontal portions of the supports 5 are provided with bearings 11 and 12, in which there are engaged shafts 13 and 14, respectively.

Upon the shaft 13 there are keyed a pair of booms 15 adapted to move with rotation of the shaft, as will be explained in greater detail.

The portion of the boom 15, adjacent the shaft 13 is enlarged as at 16 and has an arcuate slot 17. The outermost edge of the slot is provided with gear teeth 18 for intermeshing with a gear 19 keyed upon the shaft 14.

A sprocket wheel 20 is free upon the shaft 14, in alignment with a sprocket wheel 21 carried by the shaft 13, and a chain 22 is trained about the sprocket wheels 20 and 21.

A worm gear 23 is secured to the shaft 13 operable through a gear 24 mounted upon the shaft 25. Upon the opposite end of the shaft 25 there is keyed a bevel gear 26 arranged to mesh with a similar gear 27 carried by the hand wheel 28.

A clutch 29 is provided between the gear 19 and sprocket 20, whereby the sprocket 20 will be locked to the gear 19 in outward movement of the boom, but will be released upon return movement of the boom. This is accomplished by providing a ratchet gear 30 upon the sprocket 20 and a spring-pressed detent 31 upon the gear 19 for engagement with the ratchet gear 30.

A hand-wheel 32 is secured upon the shaft 14 for a purpose hereinafter explained.

The boat is denoted by 33, and is provided with eyelets 34 for engagement by quick-detachable hooks 35 carried by the booms 15.

The track 1, in the present instance, is 90 shown as two angle iron members, substantially U-shaped in cross section their open ends being presented toward one another, thereby forming a channel within which the guide rollers 7 may slide or rotate. In the case of metallic vessels, these rails may be welded to the sides of the ship and in the case a wooden structure is involved, the rails may be provided with proper fastenings, as 95 will be apparent.

The rails 1 are spaced a sufficient distance apart to accomodate a boat to be lowered, and of a length to extend from the uppermost deck to a point well below the water line of the vessel.

Reference is now made to Figure 2, wherein it will be seen that a boom 15 is disposed adjacent each track 1, thus affording clear passage-way of a boat in its outward movement.

The operation of my device is as follows, assuming that the boat is in the position shown in Fig. 1. By turning the hand-wheel 28, rotary motion is imparted to the shaft 25, through the gears 26-27 whereupon the worm 24 will be caused to rotate. Since the gear 24 is splined upon the shaft 13, the shaft is likewise caused to rotate, and consequently rotates the sprocket wheel 21. Motion is transmitted from the sprocket wheel 21 to the shaft 14 by virtue of the chain 22 and sprocket wheel 20.

It will be seen that with the rotation of the shaft 14, the booms 15 will be caused to swing into vertical position, due to the fact that the gear 19 traverses the arcuate-shaped gear 18, and, as will be understood such movement of the booms will elevate the boat 33 into a vertical position.

With the booms 15 in elevated position, the weight of the boat is disposed upon the carriages 4, and by operation of a winch or other suitable means the cable 9 may be slackened, allowing the davit to slide downwardly in the rails 1 into close proximity of the water. Further manipulation of the hand-wheel 28, by an operator within the boat 33, will effect a further movement of the booms 15, until they assume a position substantially horizontal to the vessel 2, as indicated at A in Fig. 1. Thus, the boat 33 is held a spaced distance from the vessel 2, and by reason of the short connection between the boat 33 and booms 15, the boat 33 is held against excessive swinging movement in any direction.

After launching of the boat 33, the davit is returned to its uppermost position, by operation of the winch. In this position, it would be well to explain, that the booms 15 are still in their outwardly swung position. Relation of the hand-wheel 32 will transmit rotary movement to the gear 19 since the clutch 29 is ineffective in rearward movement of the booms. Therefore, the gear 19 traverses the gear 18 in a reverse direction to that through which it passed in outward movement of the booms, and consequently brings the davit into its original position upon the vessel 2.

By providing the float 6 at the lower extremity of the supports 5, a more steady launching of the boat 33 is effected, since the float will cause movement of the davit

to correspond to that of the waves or water, in which a boat is being launched.

I claim:

1. In a davit, a support, guide rails thereon, a carriage slideable in said guide rails, booms carried by said carriage, means carried by said booms for swinging and fixedly positioning said booms relative to said carriage, and means for raising and lowering said carriage within said rails.

2. A davit comprising a supporting structure, vertically disposed guide rails, a carriage, said carriage having rollers adapted to be received within said guide rails, booms carried by said carriage, means carried by said booms for swinging and fixedly positioning said booms relative to said carriage, and means to raise and lower said carriage.

3. A davit comprising a supporting structure, vertically disposed guide rails, a carriage, said carriage having rollers adapted to be received within said guide rails, booms carried by said carriage, said booms having an arcuate gear, a second gear in mesh therewith, and means carried by said booms for operating said first and second named gears.

4. A davit comprising a supporting structure, vertical guide rails thereon, a carriage slideable thereon, swinging booms carried by said carriage, said booms being enlarged and having an internal arcuate gear, a gear mounted upon said carriage and in mesh with said arcuate shaped gear, and means carried by said booms for operating said gears.

5. A davit comprising a supporting structure, spaced parallel guide rails carried thereby, supports slidably mounted within said rails, a pair of shafts connecting said supports, a pair of booms swingably mounted upon one of said shafts, sprocket wheels carried by each of said shafts, a chain trained about said sprockets, an arcuate gear carried by each of said booms, a gear carried by one of said shafts and in mesh with said arcuate shaped gear, and means carried by said booms for operating said sprocket wheels.

6. A davit comprising a supporting structure, spaced parallel guide rails carried thereby, supports slidably mounted within said rails, a pair of shafts connecting said supports, a pair of booms swingably mounted upon one of said shafts, sprocket wheels carried by each of said shafts, a chain trained about said sprockets, an arcuate gear carried by one of said shafts and in mesh with said arcuate-shaped gear, a clutch connecting said last named gear and said sprocket wheel, a gear carried by said other named shaft, a rotatable shaft carried by said booms, a worm gear fixed upon one end of said shaft and in mesh with the last named gear, means for operating said shaft to effect outward swinging movement of said booms and means for operating said other

named shaft to effect rearward swinging movement of said booms.

7. A davit comprising a supporting structure, spaced parallel guide rails carried thereby, booms slidably mounted within said rails, transverse shafts connecting said booms at the upper ends, and a float connecting said booms at the lower end, whereby said booms will be supported by said float when positioned upon a body of water.

JULIAN W. BOURNIER.
